UNITED STATES PATENT OFFICE.

EVERETT C. MURDOCH, OF BERKELEY, CALIFORNIA, AND GEORGE J. KELLY, OF HAVERHILL, MASSACHUSETTS.

PYROPHORIC GAS-IGNITER.

1,312,862.

Specification of Letters Patent.

Patented Aug. 12, 1919.

Application filed April 21, 1915, Serial No. 22,925.

Renewed January 10, 1919. Serial No. 270,590.

To all whom it may concern:

Be it known that we, EVERETT C. MURDOCH and GEORGE J. KELLY, citizens of the United States, residing at Berkeley, in the county of Alameda and State of California, and at Haverhill, in the county of Essex and State of Massachusetts, respectively, have invented an Improvement in Pyrophoric Gas-Igniters, of which the following is a specification.

This invention relates to certain improvements in pyrophoric gas-igniters, and, more particularly to those of the so-called "tongs" type, in which a U-shaped spring frame is provided, one of the arms thereof having a transversely disposed file mounted on the end thereof, and the other having a renewable holder for the pyrophoric alloy connected thereto, in position to press the alloy against the file surface, so that, as the two arms are pressed together, the alloy will be abraded, to form the sparks, said renewable holder being commonly termed a "renewal".

Prior to our invention it has been customary to employ a form of "renewal" which consists of a tubular nipple of brass, into one end of which a small cylindrical piece of the alloy is fitted, so that it projects therefrom, the other end of the nipple being either internally screw-threaded, to receive a correspondingly threaded end-portion on the arm, or being formed to fit tightly on such end-portion, so that it will be held in this position, but may be removed. This form of holding means for the alloy is undesirable for several reasons, particularly in that practically only the portion of the alloy which projects beyond the end of the brass nipple can be used, for the reason that, as soon as the alloy becomes worn down to the end of the nipple, the relatively hard metal of the tube prevents engagement thereof with the file to an extent sufficient to produce the desired spark, and repeated attempts to produce a spark would soon wear out the file. As a result, a piece of the alloy of substantial size is unused, and, as the alloy is expensive, and only about three-fourths of it

is used, the item of loss is important. The alloy is also extremely brittle and large particles are frequently chipped off at the sides thereof, the greater the distance which it projects beyond the sleeve in which it is in-

serted, the greater being the liability that this well occur. Also, in order that a sufficiently rigid connection may be made between the nipple and the arm, it is practically necessary to provide a threaded connection therebetween, involving the formation of internal screw threads in each nipple, and, furthermore, for the sake of economy, the nipple is made of no greater diameter than is necessary for the purpose, and is, therefore, of such small size, that, if it is screwed onto the arm with some force, it is difficult to unscrew it with the fingers, making it necessary to use an implement to remove the alloy holder.

The object of our invention is to provide a means for supporting the pyrophoric alloy on the end of the arm of a gas-igniter, of the character above referred to, in such a manner that practically all of the alloy may be used before it becomes necessary to supply a new piece of alloy, and, to provide a form of holder for the alloy, which is adapted to be supplied as a "renewal", and which may be made at small expense, and, further, to provide a form of connection therefor which will securely retain the holder in position and enables it to be renewed without the use of tools, under practically all conditions.

We accomplish these objects by the means shown in the accompanying drawing, in which:—

Figures 1 and 2 are respectively an edge elevation and a bottom plan view of a pyrophoric gas-igniter, of the "tongs" type, and provided with our invention.

Figs. 3 and 6 are detail views of the alloy-holding means on an enlarged scale, Fig. 3 being a sectional view, Fig. 4, a disassembled side elevation, and Figs. 5 and 6 side and end views of the renewal.

In the drawing *a* indicates the U-shaped frame having the usual arms *a'*, *a''*, the arm *a'* bearing the transversely disposed file *b*, and the arm *a''* having an upturned end *a''*, on which the pyrophoric alloy holding means is mounted.

According to our invention, we provide an externally threaded sleeve *c*, which is mounted on the upturned end *a''*, of the arm *a''*, and is rigidly connected thereto by any suitable means, as by soldering, the particular form of permanent connection being immaterial. A coupling-ring *d* is adapted to

be threaded on the sleeve *c*, and is provided with an inwardly extending, annular lip *d*'. A cylindrical metal cup *e*, having a flat bottom and a projecting annular base flange *e'*, is provided, said cup being preferably of magnesium and having its cavity formed to receive a cylindrical piece of cerium-iron alloy *f*, which is tightly fitted therein, the side walls of the cup being thin, and its diameter, above its flange *e'* being such that it fits closely, but freely in the aperture formed at the inner edge of the lip *d*'. A flat face is formed on the top of the sleeve *c* on which the bottom of the cup *e* rests, and, to connect the cup to the arm *a*², it is merely necessary to pass the ring *d* over the cup and screw it onto the sleeve *c*, so that its lip *d* engages the flange *e* and clamps the cup firmly onto the face thereof, as shown in Fig. 3, the greater portion of the cup thus projecting beyond the top of the ring. The depth of the cup *e* is such that, when it is clamped in position, as above described, its bottom is a short distance above the top of the ring *d*, and the alloy *f* is forced into the cup until it bears against said bottom, the alloy thus being held entirely in the projecting portion of the cup, and its outer end being, preferably, flush with its edge. The walls of the cup are of thin metal, and, as above stated, the metal employed is magnesium, the hardness of which is substantially less than that of the alloy and is, therefore, adapted to be cut away by the file more readily than the alloy. The metal of the cup will thus be worn down as fast as the alloy, and will act to hold the alloy in position and prevent it from being broken off in large chips, while this is taking place. This action will continue until the sides of the cup and the alloy are worn down to the bottom of the cavity, and the alloy is thus practically all used, and when this occurs, a new cup containing the alloy, or cartridge, will be substituted as will be obvious.

The above-described construction is advantageous, not only because the construction makes it possible to use all the alloy, but because it enables the provision of a pyrophoric renewal device which may be made at small expense as the whole cup may be stamped out of metal, so that practically no machine work is required, and the cutting of a thread therein is unnecessary. The coupling-ring is also of sufficient size to enable it to be readily unscrewed and returned in its place without the use of tools.

We claim:—

1. In a pyrophoric igniter, an externally threaded support having a face at one end, a coupling ring threaded on said support and having an inwardly extending lip, and a pyrophoric-alloy-holder constructed to extend through said ring to support the alloy therebeyond, and having a lateral projection arranged to be engaged by said lip to clamp said holder against said face.

2. In a pyrophoric igniter, an externally threaded support having a face at one end, a coupling ring threaded on said support, and having an inwardly extending, annular lip, and a pyrophoric-alloy-holder of cylindrical form, extended through said ring and seated on said face, said holder having a laterally projecting, annular flange arranged in position to be engaged by said lip to clamp said holder on said face.

3. In a pyrophoric igniter, an externally threaded support, a coupling ring threaded on said support and having an inwardly extending lip, and an alloy-receiving cup seated on said support and extending through said ring, said cup having a lateral projection at its base engaged by said lip, to hold said cup in position on said support.

4. In a pyrophoric igniter, an externally threaded support having a face at one end, a coupling ring threaded on said support and having an inwardly extending lip, and a cylindrically shaped holder arranged to extend through and project beyond said ring, and having a lateral projection arranged to be engaged by said lip to clamp said holder against said face, the projecting portion of said holder having a pyrophoric-alloy-receiving cavity of a depth less than the extent to which the holder projects beyond said ring.

5. In a pyrophoric igniter, a support, a cup seated on said support and having a transversely projecting flange at its base, means arranged to engage said flange and said support to clamp said cup on the seat of said support, and a piece of pyrophoric metal supported in said cup beyond said engaging means.

In testimony whereof we have signed our names to this specification, in the presence of two subscribing witnesses.
